(57) **CLAIM**

The ornamental design for an automobile, as shown and described.

DESCRIPTION

FIG. 1 is a Front Profile view of the automobile showing my new design;

FIG. 2 is the left side(driver's side) profile view thereof. The right side view (i.e., the passenger side) is a mirror image of the FIG. 2 left side (driver's side) view of my design;

FIG. 3 is a rear profile view thereof; and,

FIG. 4 is an overhead view thereof.

The whited out areas around the rims, license plate and front grille represent portions of the automobile that form no part of the claim.
